UNITED STATES PATENT OFFICE

HERBERT E. RIDER, OF BROOKLYN, NEW YORK, ASSIGNOR, BY MESNE ASSIGNMENTS,
TO LIBERTY AEROIL BURNER, INC., A CORPORATION OF NEW YORK.

VAPORIZING-TUBE.

1,269,001.

Specification of Letters Patent. Patented June 11, 1918.

Application filed September 11, 1917. Serial No. 190,832.

To all whom it may concern:

Be it known that I, HERBERT E. RIDER, a citizen of the United States, residing at Brooklyn, in the county of Kings and State 5 of New York, have invented certain new and useful Improvements in Vaporizing-Tubes; and I do hereby declare the following to be a full, clear, and exact description of the invention, such as will enable others 10 skilled in the art to which it appertains to make and use the same.

This invention relates to oil burners, and more particularly to that type of burner in which the heavier hydrocarbon oils may be 15 employed as fuel.

It has for an object to provide an improved retort in which accumulation of carbon is prevented.

A further object of the invention is to 20 provide a retort of simple construction containing means operable by changes of temperature to prevent such accumulation of carbon.

Further objects will be apparent from the 25 following specification, appended claims, and drawings, in which:

Figure 1 shows the complete apparatus as applied to a steam boiler, illustrating 30 parts of the boiler and fire box broken away, Fig. 2 shows in section, a portion of the supply line,

Fig. 3 is a perspective view of a small portion of the vaporizing tube showing the shell removed from a section of the rods, 35

Fig. 4 is a perspective view of a rod removed, and,

Fig. 5 shows an enlarged perspective view of the vaporizing tube in cross section, and

Fig. 6 is an enlarged sectional view of the 40 fastening of one end of the rods.

In this invention, the retort and burner may be considered as for use with such heavy hydrocarbons, as precipitate carbon, upon heating to vaporize. The apparatus is 45 intended to receive the heavy oil, feed it in proportions sufficient to create the desired heat units for generating steam or for other heating purposes, to reduce the oil to

a vapor which is fed to the burner, and to maintain a free passage through a vaporizing coil by dislodging the carbon precipitate or deposits through action of certain parts of the apparatus.

Referring more specifically to the drawings, there is shown a steam boiler 10 having an oil burner placed in the fire box and this burner comprises a plurality of burner tubes 11 which have sections of a distributing duct 12 formed thereon. These burner tubes are secured to each other, with the 60 sections 12 forming a continuous duct, and intermediate burner tubes may be included to build up a burner of the desired capacity. The central duct section 12 has a depending nipple 13 which forms an admission inlet for 65 a gaseous mixture, and below this opening, a nozzle 14 is placed. This nozzle is provided with a needle valve actuated by the hand wheel 15 on the valve stem, and one end of a retort 16 is connected to the nozzle 70 as by the coupling 17.

The retort 16 comprises a thin shell in which, rods or wires 18, 19 and 20 are snugly fitted. The rods are corrugated, or roughened and are of different metals, so that 75 when changes of temperature occur, the individual rods will expand or contract in different ratios, and owing to the relative movement, they will dislodge any carbon deposits which would otherwise tend to 80 form and accumulate. The corrugations in these rods form abrasive surfaces which keep the interstices between the rods and inner wall of the shell clean for the free 85 passage of oil.

The retort 16 is coiled over the burner head, so that oil passing through this retort will be heated to convert it into a vapor. The other end of this retort is secured in a fitting 21 which is shown as a T, having 90 an oil supply pipe 22 attached to the branch, and having the proximal ends of the rods 18, 19 and 20 enter the extension, where they are brazed or otherwise secured as suggested in Fig. 6, but having the extreme end 95 closed against the escape of oil. By fasten-

ing the ends of these rods, the expansion of the individual rods is utilized, but a free passage for the oil is retained through the interstices between the rods, and within the shell. In placing the rods in close bearing relation, heat is readily conducted into the interior of the tube to convert the oil into a vapor, and the corrugated or interrupted surfaces form passages communicating between the several interstices.

The oil supply pipe 22 is provided with a pressure controlled valve comprising the chamber 23 with a diaphragm 24 therein, and this diaphragm is attached to a valve 24' which controls the oil feed. The upper chamber is connected with the steam dome of the boiler as by the pipe 25 and through an adjusting means A, any boiler pressure may be adapted to reduce the oil supply.

Should the supply pipe become separated or should the oil supply flow at a greater velocity than is necessary for the burner, an automatic check valve 26 in the casing 27 seats and closes the passage through the pipe 22. A spring and adjusting nut will afford adjustment of this valve to regulate a normal flow, but any excessive flow will automatically seat the valve.

The pipe line 22 is connected with and extends into an oil tank 28 to a point near the bottom or it may be connected with the tank near the bottom. This tank is further provided with a gage 29 for determining the air pressure and with a source of air pressure as through the pipe 30 and air pump 31. The tank also has a filling opening which is closed as by the cap 32. A manually operated valve 33 may serve to cut off the oil supply when desired.

It is thought that the operation of this device is obvious from the foregoing, and it is clearly seen that for use in connection with a steam boiler, after the requirements necessary in starting the operation have been carried out, the oil supply may be established, and the burner started. When the burner is in operation, the retort serves to convert the heavy oil into a gas which along with air is fed to the burner through the admission inlet 13. By heating the retort, and allowing it to cool, the expandible rods will serve to convey heat into the retort, and also keep it clean.

Adjustment of the pressure operated valve 55 and check valve may be made when the working conditions of the apparatus have been established, and by the desired air pressure, a uniform flow of oil may be obtained through the retort. The indications of 60 "iron", "brass", and "copper" for the rods 18, 19 and 20 are used only to indicate that metals having different coefficients of expansion are employed and are not intended to

indicate that the invention is limited to the use of these three metals.

Other modifications may be made in view of the appended claims without departing from the spirit of this invention, and the drawings are for illustrative purposes only.

Having thus described this invention I claim:

1. In an oil burner of the class described, a retort comprising a shell and a plurality of corrugated rods therein of different metals having different coefficients of expansion.

2. In an oil burner of the class described, a retort comprising a shell, and a plurality of rods of metals having different coefficients of expansion, secured at one end in said shell, said rods in their different expansions between themselves and said tube preventing accumulation of carbon on said rods and in said tube.

3. In an oil burner of the class described, a retort comprising a tube, and a plurality of continuous rods snugly placed therein secured at one end in said tube, and being of different metals having different coefficients of expansion, said rods being corrugated to prevent accumulation of carbon on said rods and in said tube.

4. In an oil burner of the class described, a burner, a coil mounted over said burner comprising a tube and a plurality of corrugated rods snugly placed therein and secured at one end, said rods serving to conduct heat through the tube, and being of different metals having different coefficients of expansion, said rods forming interstices therebetween for the passage of oil.

5. In an oil burner of the class described, a burner head comprising a plurality of detachable burner tubes, a distributing duct supporting said burner tubes, disposed centrally under said burner tubes, an inlet for a mixture of air and gas formed in the distributing duct, a nozzle under said inlet, and a retort comprising a shell having a plurality of rods of different metals therein, connected to said nozzle.

6. In an oil burner of the class described, a burner head, a retort disposed over said burner head, said retort terminating in a nozzle for supplying a gaseous mixture to said burner head, said retort comprising a thin tube having a plurality of small rods of continuous length snugly fitted therein to conduct heat throughout said tube, said rods being of different metals to utilize the different degrees of expansion for the purpose of abrasively preventing accumulation of carbon within said tube.

7. In an oil burner, a retort comprising a shell and a plurality of rods of different metals and different coefficients of expansion

confined within said shell to divide the passage through the shell into a plurality of small interstices, and for the purpose of abrasively dislodging any precipitation of carbon in their independent movements.

8. A liquid fuel retort including means operable by temperature changes for abrasively dislodging precipitation of carbon.

9. A liquid fuel retort including means operable by temperature changes for auto-

matically dislodging precipitated carbon therefrom by abrasion.

10. A liquid fuel retort having a plurality of devices therein, arranged with interstices therebetween, and operable by temperature changes for the purpose of dislodging precipitated carbon and similar foreign matter.

In testimony whereof I affix my signature in presence of two witnesses.

HERBERT E. RIDER.
